TABLECLOTH

Richard A. Fees, Ardsley, Pa., assignor to Quaker Lace
Company, Philadelphia, Pa.

Filed Feb. 20, 1968, Ser. No. 10,645

Term of patent 14 years

(Cl. D92—26)

The figure is a plan view of slightly more than quarter section of a tablecloth showing my new design, the other three sections being identical with the section here disclosed, arranged in proper relation to complete the tablecloth. The section disclosed is shown over a dark background to bring out the details of the design.

I claim:

The ornamental design for a tablecloth, substantially as shown and described.
